UNITED STATES PATENT OFFICE.

WALTER F. MORSE, OF NORWOOD, MASSACHUSETTS.

SASH-FASTENER.

SPECIFICATION forming part of Letters Patent No. 368,960, dated August 30, 1887.

Application filed May 25, 1887. Serial No. 239,286. (No model.)

To all whom it may concern:

Be it known that I, WALTER F. MORSE, of Norwood, in the county of Norfolk, State of Massachusetts, have invented a certain new and useful Improvement in Sash-Fasteners, of which the following is a description sufficiently full, clear, and exact to enable any person skilled in the art or science to which said invention appertains to make and use the same, reference being had to the accompanying drawings, forming part of this specification, in which—

Figure 1 is an elevation of a window-casing embodying my improvement, a portion of the window-sash being shown in cross section and the casing and window represented as broken off; Fig. 2, a vertical transverse section of the same, taken on line $\alpha\alpha$ in Fig. 1; Fig. 3, a like view taken on line yy in Fig. 1; Fig. 4, a horizontal section taken on line zz in Fig. 2, and Fig. 5 a like view taken on line mm in Fig. 2.

Like letters of reference indicate corresponding parts in the different figures of the drawings.

My invention relates more especially to that class of sash-fasteners which are inserted in the casing of the window and are adapted to engage the stile of the sash; and it consists in a novel construction and arrangement of parts, as hereinafter more fully set forth and claimed, the object being to produce a simpler and more effective device of this character than is now in ordinary use.

The nature and operation of the improvement will be readily understood by all conversant with such matters from the following explanation:

In the drawings, A represents the window-casing, B the stile of the uppersash, C the stile of the lower sash, and H the frame-work of the window.

The outer edge of each of the stiles B C is provided with a vertical centrally-disposed groove, in which is secured a toothed or serrated rack, b, (see Figs. 3 and 4,) said racks being so arranged that the ends of the teeth are flush with the edges of the stiles. Mortises G are cut in the frame-work H slightly

above and below the meeting-rails of the sashes, and the casing A is provided with openings i, 50 corresponding with said mortises. Metallic plates K are disposed in the mortises G, said plates being adapted to work laterally therein, and provided at their outer ends with inwardly-projecting flanges l, having teeth p 55 adapted to engage the serrations in the racks b. Plates J are respectively secured to the casing A over the openings i, said plates being provided with a horizontally-arranged stud or nipple, d. A push-rod, g, is fitted to 60 work horizontally in a hole in said stud, and provided at its outer end with a knob or handle, h, the inner end of said rod being centrally and rigidly secured to the inner end of the plate K. A coiled spring, k, is disposed around 65 the rod g within the hole s in the stud d, said stud being counterbored to receive the spring, which acts expansively to force said rod outward. A plate, r, provided with a vertical slot, w, is disposed on the stud d in such a manner that it can be moved vertically thereon. The upper end of said plate is provided with an outwardly-projecting flange, t, and downwardly-projecting flange v, having a vertical slot, 14, and when the plate r is forced downward on the stud d the neck of said knob enters the slot 14, and thereby prevents the rod g from being forced inward or outward, as the case may be.

It will be understood that the fastening for 80 the stile B is provided with a longer plate K than the fastening for the stile C, as it is required to reach to the center of the stile B, so that its toothed flange l will engage the serrated bar b in said sash.

In the use of my improvement, when the sashes are closed and locked, as shown in Fig. 1, if it is desired to open the window, the knob h is pressed inward, thereby disconnecting the teeth p from the serrations of the bar b and 90 permitting the sash to be moved in a manner which will be readily obvious without a more explicit description. By moving the plate r downward on the stud d until the neck of the knob h enters the slot 14, (see Fig. 2,) the 95 spring k may be kept depressed and the teeth

p of the plate *K* disengaged from the serrations of the rack *b*, as described, until it is desired to lock the window again.

Having thus explained my invention, what I claim is—

5 In a sash-fastener, the plate *r*, having the slot *w* and provided with the flange *v*, having the slot 14, in combination with the plate *J*, having the stud *d*, the rod *g*, provided with the

knob *h* and spring *k*, the plate *K*, having the flange *l*, provided with teeth *p* and the serrated rack *b*, said plate *r* being mounted on the stud *d* and adapted to engage the knob *h*, substantially as described.

WALTER F. MORSE.
